ATTORNEY

UNITED STATES PATENT OFFICE.

BERT C. DODDS, OF WOODLAND, CALIFORNIA.

ADJUSTABLE LADDER-SHELF.

1,260,525.

Specification of Letters Patent. Patented Mar. 26, 1918.

Application filed November 12, 1917. Serial No. 201,528.

To all whom it may concern:

Be it known that I, BERT C. DODDS, a citizen of the United States, residing at Woodland, in the county of Yolo and State 5 of California, have invented certain new and useful Improvements in Adjustable Ladder-Shelves, of which the following is a specification.

This invention relates to an improved ladder shelf and the principal object of the invention is to provide a shelf which may be connected with a ladder and which may be adjusted so that the shelf will at all times be level without respect to the inclination 15 of the ladder.

Another object of the invention is to so construct the shelf that it may be adjusted transversely of the ladder to extend either directly from the ladder or to one side 20 thereof.

Another object of the invention is to so construct this shelf that the bracket thereof may be easily and quickly connected with the rungs of the ladder and securely held in 25 place when connected with the ladder.

Another object of the invention is to so construct this shelf that it will be held against side play and thus danger of tilting prevented.

30 This invention is illustrated in the accompanying drawings, wherein:—

Figure 1 is a view in elevation showing the improved bracket connected with a ladder,

35 Fig. 2 is a view showing the improved bracket in side elevation and the ladder in section,

Fig. 3 is a vertical sectional view taken along the line 3—3 of Fig. 2,

40 Fig. 4 is a vertical sectional view taken along the line 4—4 of Fig. 3 with certain other portions of the bracket in place,

Fig. 5 is a fragmentary sectional view taken along the line 5—5 of Fig. 4.

45 This shelf is for use in connection with a ladder indicated in general by the numeral 10 and will be suspended from one of the rungs 11 by the hooks or suspending rods 12, the upper or hooked ends of which engage one rung and the lower end portions of which will rest upon a lower rung. Sleeves or extensions 13 fit upon the lower end portions of these rods 12 and are held in a set 50 position by the set screws 14, the sleeves being provided so that the rods may be lengthened if the device is used upon a ladder hav-

ing the rungs set far apart. These rods or hooks 12 are connected with the back-board or body 15 of the shelf by brackets 16 and at the lower end of the back-board there is 60 provided a bracing rod or hook 17 pivotally connected with the body by the bearings 18 and having its hooked end portion 19 adjustably and releasably held in a set position by the set screw 20. This bracing hook may be 65 swung to either side of the shelf and when in an operative position as shown in Fig. 1, will rest upon one of the hooks 21. By providing an adjustable mounting for this bracing hook 17, the hook may be turned in the 70 proper direction according to the inclination of the ladder and thus the brackets prevented from having transverse movement upon the ladder.

A bracket plate 22 is pivotally connected 75 with the body or base-board 15 by the pivot pin or bolt 23 and carries a housing 24 in which is slidably mounted a latching pin 25 yieldably held to extend through openings formed in the latch plate 26 by the springs 80 27. It will thus be seen that this bracket plate may be turned to extend at the desired angle and may be releasably locked in the adjusted position. Upper and lower sets of hinge ears 28 and 29 extend from the 85 bracket plate 22 and serve to pivotally mount the rack 30, the rack being provided with hinge ears 31 and 32 extending between the hinge ears 28 and 29 and provided at its lower end with a hinge element 90 33. A pivot pin 34 connects the hinge ears 31 with the hinge ears 28 and a pivot pin or rod 35 of greater length than the rod 34 connects the ears of the hinge element 32 with the hinge ears 29 and extends down to pass 95 through the hinge ears of the hinge element 33 and also extends upwardly through a latch plate 36. This latch plate 36 extends into a slot formed in the lower portion of the latch housing 37 and is provided with 100 openings to receive the latching pin 38 slidably mounted in the housing 37 and yieldably held to extend through the rack plate 36 by a spring 39. This rack 30 can therefore be turned and releasably held in an 105 adjusted position for a purpose to be hereinafter brought out. A lever or bar 40 is pivotally connected with the hinge element 32 and has arms 41 extending therefrom to support a platform or shelf 42. A latching 110 pawl 43 for the lever or bar 40 is slidably mounted thereon, and extends to engage the

teeth of the double rack 30 so that this latch lever may be releasably held in an adjusted position. An actuating pin 44 is connected with this pawl 43 and carries a spring 45 yieldably holding the pawl in engagement with the rack.

When in use, the bracket shelf will be connected with the ladder as shown in Figs. 1 and 2 and after the ladder has been put in place, the plate 22 will be turned to the vertical position and releasably locked. The latch lever or bar 40 will then be moved to bring the platform or shelf 42 to a horizontal position so that articles placed thereon will not have a tendency to slide off and after this has been done, the latch 38 may be released and the bracket or rack member 30 may then be swung to one side and the latch 38 then released to lock the bracket in this position. It will thus be seen that the bracket shelf may be adjusted for the inclination of the ladder in case the ladder does not rest upon level ground and after the bracket 30 has been brought to extend vertically, the shelf may be moved to extend horizontally thus providing a steady support for any article which it may be desired to place upon the shelf. It will be further seen, that this shelf may be retained either in the position shown in Figs. 1 or 2 or it may be turned to one side of the ladder where it will be out of the way.

What is claimed is:—

1. A shelf bracket comprising a body, means for connecting the body with a support, a latch plate carried by the body, a supporting plate pivotally connected with the body, means carried by the supporting plate for engaging the latch plate to releasably hold the supporting plate in an adjusted position, a bracket pivotally connected with the supporting plate for movement transversely of the body and provided with rack teeth, a latch plate carried by the bracket, a latch carried by the supporting plate for engaging the latch plate of the bracket and releasably holding the bracket in an adjusted position, a latch lever pivotally connected with the bracket and having its latch positioned for engagement with the rack teeth of the bracket, a supporting arm extending from the latch lever, and a platform carried by the supporting arm.

2. A shelf bracket comprising a body, means for connecting the body with a support, a supporting plate pivotally connected with the body, means for releasably holding the supporting plate in an adjusted position, a bracket pivotally connected with the supporting plate for swinging movement transversely of the body, the bracket being provided with teeth forming a rack, means for releasably holding said bracket against swinging movement, a latch lever pivotally connected with the bracket and having its

latch positioned for engagement with the rack teeth of the bracket, an arm extending from the latch lever, and a platform carried by the arm.

3. A shelf bracket comprising a body, a supporting plate pivotally connected with the body and releasably held in a set position, a bracket pivotally connected with the supporting plate for swinging movement transversely of the body, the bracket being arcuate and provided with teeth forming a rack, means for releasably holding the bracket against swinging movement, a lever pivotally connected with the bracket, a latch movably carried by the lever and yieldably held to engage the rack teeth of the bracket, and a shelf connected with the lever.

4. A shelf bracket comprising a body, a supporting plate pivotally connected with the body and releasably held against movement, a bracket pivotally connected with the supporting plate for swinging movement transversely of the body, a latch plate connected with the bracket, a latch carried by the supporting plate and engaging the latch plate to releasably hold the bracket against swinging movement, a lever pivotally connected with the bracket and releasably held against movement, and a shelf connected with the lever.

5. A shelf bracket comprising a body, a supporting plate pivotally connected with the body and releasably held against movement, hinge ears extending from the supporting plate, a bracket provided with hinge elements pivotally connected with the hinge ears of the supporting plate, means releasably holding the bracket against swinging movement, a lever pivotally connected with one of the hinge elements of the bracket, means for releasably holding the lever against movement, and a shelf connected with the lever.

6. A shelf bracket comprising a body, a supporting plate pivotally connected with the body and releasably held against movement, hinge ears extending from the supporting plate, a bracket provided with hinge elements, a latch plate carried by the bracket, pivot pins connecting the hinge elements of the bracket with the hinge ears of the supporting plate, one of the hinges extending through the rack plate, a latch carried by the supporting plate and engaging the latch plate of the bracket to releasably hold the bracket against swinging movement, and a shelf connected with the bracket.

7. A shelf bracket comprising a body, a support pivotally connected with the body and releasably held against movement, a bracket pivotally connected with the support for swinging movement transversely of the body and releasably held against swinging movement, and a shelf pivotally connected with the bracket for vertical swing.

ing movement and releasably held against movement.

8. A shelf bracket comprising a body, supporting hooks connected with the body for engaging the rungs of a ladder, a bracing hook pivotally connected with the body, means for supporting the bracing hook to extend transversely of the body and engage a side bar of the ladder, supporting means connected with the body, a bracket connected with the supporting means, and a shelf connected with the bracket.

9. A shelf bracket comprising a body, rods connected with the body and having their upper ends bent to provide hooks, sleeves mounted upon the lower ends of the rods to provide extensions, a rod pivotally connected with the lower end portion of the body, an extension connected with the rod

and having its free end portion bent to provide a hook, means for releasably supporting the last mentioned rod extending to one side of the body, a support connected with the body, and shelf carrying means connected with the supporting means.

10. A shelf bracket comprising a body, a support pivotally connected with the body, a bracket pivotally connected with the support, and a shelf pivotally connected with the bracket, the supporting bracket of the shelf being releasably held in a set position.

In testimony whereof I affix my signature in presence of two witnesses.

BERT C. DODDS.
